SHIRT COLLAR

Robert W. McCreery, Port Washington, N. Y., assignor to Phillips-Jones Corporation, New York, N. Y., a corporation of New York

Application January 18, 1952, Serial No. 267,069

1 Claim. (Cl. 2—131)

1

My invention relates to a new and improved foldable shirt-collar which is especially adapted for sport shirts.

The invention relates to a collar which, when folded, has a top longitudinal seamless fold-line, along which at least some of the fabric layers of the collar are bent downwardly to provide a neck-band and an outer top or face-band. This type of collar is known in the trade as a one-piece collar, even though it is made of a plurality of layers of fabric, because the neck-band and the top or face-band have layers which are integral at said top seamless longitudinal fold-line.

In distinction, a collar which comprises a neck-band and a top or face-band which are originally made separately, and which are subsequently sewed to each other along the top line of the collar, is designated as a two-piece collar. Such two-piece collars are illustrated in U. S. Patent No. 1,829,939, dated November 3, 1931 and No. 1,897,486, dated February 14, 1933.

The one-piece collar is used extensively on sport shirts which can be worn open at the neck.

As hitherto made, it has been difficult to provide a proper top longitudinal fold-line in a one-piece collar. Such collars are made and ironed in the flat condition. When it is attempted to bend the collar around the neck, the collar wrinkles and forms irregular pleats at its top longitudinal fold-line, which injures the appearance of the collar and makes it uncomfortable.

There is no natural top longitudinal fold-line in prior one-piece shirt-collars, and it is necessary to guess at the proper line of longitudinal fold.

According to the preferred embodiment of my invention, to which the invention is not limited, I provide a one-piece collar which is made of five layers of fabric. These five layers include an outer face-layer and an inner face-layer, which are folded along the top, longitudinal fold-line of the collar and which have panels which are located both in the neck-band and in the top.

There is also a main inner layer which is folded along said top longitudinal fold-line. Said main inner layer is located inwardly of said face-layers, and has panels in both the neck-band and top.

There is also a rear or neck-band reinforcing layer, which is located wholly in the neck-band and which is not folded at said longitudinal fold-line. This is located directly adjacent the rear or neck-band panel of the main inner layer and between the main inner layer and the outer face-layer.

There is also a face-band reinforcing layer, 55

which is located wholly in the face-band, and which is not folded at said longitudinal fold-line.

This face-band reinforcing layer is located directly adjacent the front panel of said main inner layer and between the main inner layer and the outer face-layer.

The outer face-layer is folded at the top of the collar to provide a rear panel which is located outwardly of and directly adjacent said rear reinforcing layer; and to provide a front panel which is located outwardly of and directly adjacent said front reinforcing layer.

These front and rear reinforcing layers are sewed to the main inner layer, with the adjacent longitudinal edges of said reinforcing layers spaced transversely from each other, in order to provide a longitudinal fold-zone.

Numerous other objects and elements of my invention are disclosed in the annexed description and drawings, which illustrate a preferred embodiment of my invention.

Fig. 1 is a top plan view which shows the five layers or pieces of fabric from which the collar is made;

25 Fig. 2 is a top plan view, which shows the front and rear reinforcing pieces or layers initially sewed to the main inner layer by curved longitudinal lines of stitches at the adjacent longitudinal edges of said reinforcing pieces or layers;

30 Fig. 3 is a section on the line 3—3 of Fig. 3;

Fig. 4 is a plan view, which shows how the two face pieces or layers are stitched to the three pieces or layers of Fig. 2, in order to provide a turnable collar-form;

35 Fig. 5 is a section on the line 5—5 of Fig. 4;

Fig. 6 is a plan view of said collar-form of Figs. 4 and 5, after said collar-form has been turned;

Fig. 7 is a section on the line 7—7 of Fig. 6;

40 Fig. 8 is a perspective view which shows the turned collar-form of Figs. 6 and 7, folded along the longitudinal fold-line of the collar; and

Fig. 9 is a section on the line 9—9 of Fig. 8.

Figs. 1, 2, 4 and 6 are substantially to the 45 same scale and they accurately show the shapes and proportion of the parts.

The main inner layer or piece 1, which is folded as shown in Fig. 9 to provide a front panel and a rear panel, has a top longitudinal convex edge 50 1d, a bottom longitudinal edge 1c which has the double curvature shown in Fig. 1, straight side edges 1a and 1b which are upwardly inclined towards each other, top corners 1e and 1f, and bottom blunted corners 1g and 1h.

Said main inner layer 1 is made of soft and

flexible material. As one example, this may be a woven cotton lawn fabric. Such lawn fabric, when just off the loom, woven in a width of 40 inches, has 6.90 yards per pound of cotton. As one practical working example, the length of the longitudinal straight line between top corners $1e$ and $1f$ has a length of 15.5 inches, and the height of main inner piece 1 is four inches at its vertical median line.

The front and rear reinforcing pieces or layers 3 and 2 are made, as one example, of woven cotton lining fabric. Such lining fabric, in a width of 38 inches, has a weight of one pound per three yards.

Front reinforcing layer 3 has a top longitudinal concave edge $3a$, top corners $3g$ and $3h$, a bottom double-curvature longitudinal edge $3b$, straight upwardly convergent edges $3c$ and $3d$, and bottom blunted corners $3e$ and $3f$.

Rear reinforcing layer 2 has top and bottom longitudinal convex edges $2b$ and $2a$, top corners $2g$ and $2h$, upwardly convergent side edges $2c$ and $2d$, and bottom corners $2e$ and $2f$.

The first operation is to assemble main inner layer 1 with rear reinforcing layer 2 and front reinforcing layer 3 , by means of four curved and longitudinal rows of stitches 4 , which have the shape shown in Fig. 2. The top edges $1d$ and $2b$ are then coincident; bottom edges $1c$ and $3b$ are then coincident; side edges $1a$, $2c$ and $3c$ are then coincident; and side edges $1b$, $2d$ and $3d$ are then coincident, and the stitches 4 extend continuously between said coincident side edges.

Fig. 2 shows some of stitches 4 omitted, and parts of layers 2 and 3 bent, in order to show the underneath layer 1 .

An intermediate longitudinal fold-zone 5 , of single thickness, is thus provided between edges $2a$ and $3a$.

The facing layers 6 and 7 are made of any suitable facing fabric or material.

The facing layer 6 has a top longitudinal convex edge $6d$, a bottom longitudinal double-curvature edge $6c$, and upwardly convergent side edges $6a$ and $6b$.

The facing layer 7 has a top longitudinal convex edge $7d$, a bottom double-curvature longitudinal edge $7c$ and straight and upwardly convergent side edges $7a$ and $7b$.

The facing layers are originally assembled in abutting relation with the three layers of the initial assembly of Fig. 2, by means of side stitches along the two side lines 8 , and by bottom stitches along the single line 9 . The representation of the stitches at the right side line 8 is omitted in Fig. 4, and the representation of some of the stitches along line 9 is also omitted, in order to show the relation between the five layers of Fig. 4.

These five layers are not stitched or otherwise connected to each other in Fig. 4 along their four coincident top convex edges E .

The collar-form of Fig. 4 is then turned, so that the inner layers 1 , 2 and 3 are located between the facing layers 6 and 7 . The convex top edges of the flat turned form of Fig. 7 are coincident.

The flat turned form of Figs. 6 and 7 is now folded along the median longitudinal line of the longitudinal folding-zone 5 . In the folded collar of Figs. 8 and 9, the top edge of rear reinforcing layer 2 is its convex edge $2a$ and the top edge of front reinforcing layer 3 is its concave edge $3a$.

The folded collar is thus provided with a top longitudinal fold which is made of only three layers of fabric, namely, the layers 1 , 6 and 7 .

The flat turned form is thus folded naturally to provide a neck-band N and a face-band or top F without any substantial puckers at the fold-zone, when the folded collar is bent to conform to the neck.

As shown in Fig. 9, the face layer 6 has a front panel which has an upwardly bent flap $6k$, which abuts and is directly adjacent the body of the front panel of face layer 6 .

The face layer 7 has a front panel which has an upwardly bent flap $7k$, which abuts flap $6k$.

The front reinforcing layer 3 has an upwardly bent flap $3k$, which abuts flap $7k$.

The front panel of main common layer 1 has an upwardly bent flap $1k$, which abuts the body of said front panel and flap $3k$.

Hence the front bottom edge-portion of the face-band F of the folded collar has eight layers of fabric $7-3-1-1k-3k-7k-6k-6$, from the front face of the neck-band F to its rear face. These eight layers are fixed to each other by the stitches 9 and the inwardly bent flaps $1k-3k-7k-6k$, have coincident inner or upper edges.

The bottom edge E of the neck-band N is sewed to the neck-opening of the shirt. The neck-band has four layers of fabric, and the collar has eight layers at and adjacent the top longitudinal fold-line.

I have disclosed a preferred embodiment of my invention, but numerous changes and omissions and additions and substitutions can be made without departing from its scope.

Thus, I can omit either of the reinforcing layers 2 and 3 , although the use of both said layers is highly preferred.

The tops of reinforcing layers 2 and 3 extend substantially to the fold of the face layer 7 and below the fold of the collar, as shown in Fig. 9. If only one reinforcing layer 2 or 3 is used, the top of said single reinforcing layer has the respective position which is above mentioned.

Whenever I refer to stitches, I can use equivalent fastening or fixing means.

The folded collar shown in Fig. 9 comprises an outer folded layer 7 , an intermediate folded layer 1 , and an inner folded layer 6 . Each said foldable layer is continuous at the seamless top longitudinal fold of the collar and each said folded layer has a neck-band panel and a face-band panel. The neck-band N also includes a neck-band reinforcing layer 2 , which is located intermediate the neck-band panels of the outer folded layer 7 and of the intermediate folded layer 1 . The face-band F also includes a face-band reinforcing layer 3 which is located intermediate the face-band panels of the outer folded layer 7 and the intermediate folded layer 1 . The neck-band N is of equal thickness and it consists of the neck-band panels of the folded layers 7 , 1 and 6 and the neck-band reinforcing layer 2 , which abut each other in the neck-band N .

I claim:

A collar comprising an integral inner foldable layer having a neck-band panel portion and a face-band panel portion, an integral intermediate foldable layer having a neck-band panel portion and a face-band panel portion, an integral outer foldable layer having a neck-band panel portion and a face-band panel portion constituting the visible portion of the collar when the collar is folded, a face-band reinforcing layer disposed between the face-band panel portion of said intermediate and outer foldable layers, a neck-band reinforcing layer disposed between the neck-band panel portions of said intermediate

ate and outer foldable layers, each of said reinforcing layers being substantially stiffer than said intermediate foldable layer and the adjacent edges of said reinforcing layers being spaced apart to form a fold zone, all said face-band panel portions and said face-band reinforcing layer having upwardly bent bottom flaps which are fixed to each other and which are located between the lower part of the face-band panel of said inner layer and the lower part of the face-band panel of said outer layer, the upwardly bent flap of said face-band reinforcing layer being disposed between the upwardly bent flap of

said intermediate layer and the upwardly bent flap of said outer layer.

ROBERT W. McCREEERY.
